PAPER-HANDLING MECHANISM FOR DUPLICATING MACHINES

Alfred Marchev, La Grange, and Robert F. Morrison, Oak Park, Ill., assignors to Ditto, Incorporated, Chicago, Ill., a corporation of West Virginia

Application April 16, 1938, Serial No. 202,398

7 Claims. (Cl. 101—132)

The invention relates to paper handling mechanism for duplicating machines and is particularly adapted to be embodied in duplicating machines wherein copy sheets are pressed against data carried by a rotatable duplicating drum, the copy sheets being advanced one by one to the duplicating drum and after being brought into contact with the data thereon are then discharged onto a table or tray.

10 A duplicating machine embodying one form of the invention is of the type wherein a master sheet carrying the data to be duplicated, is mounted upon the duplicating drum and each copy sheet is moistened with a solvent before it is advanced to the duplicating drum for the duplicating operation. The machine comprises conveyor mechanism for receiving and advancing the copy sheets after they have been brought into contact with the master sheet, the construction being such that each copy sheet is discharged from the machine onto a tray in such manner that the data duplicated on each copy sheet is visible to the operator as it passes to the receiving tray. Each copy sheet is also accessible to the operator so that the operator may return it to copy sheet mechanism for advancing it through the machine a second time. Thus, in some instances, it is desirable to obtain a predetermined number of copies of a master sheet upon suitable copy sheets and then pass one or more of the copy sheets through the machine a second time so that the data will be duplicated on both sides thereof.

Other objects and advantages will become apparent as the following detailed description progresses, reference being had to the accompanying drawings, wherein—

Fig. 1 is a vertical longitudinal section taken through a duplicating machine which embodies the invention.

Fig. 2 is a plan view of the improved duplicating machine.

Fig. 3 is an end elevation of the improved duplicating machine.

45 Fig. 4 is a side elevation of certain conveyor mechanism which forms part of the improved duplicating machine.

Fig. 5 is a section taken on line 5—5 of Fig. 4.

Fig. 6 is a view looking at the other side of the conveyor mechanism.

Fig. 7 is a side elevation of a conveyor mechanism which embodies another form of the invention and may be employed in place of the conveyor mechanism shown in Figs. 1 to 6, inclusive.

Fig. 8 is a fragmentary back view of the conveyor mechanism shown in Fig. 7.

Fig. 9 is a fragmentary section taken on the line 9—9 of Fig. 8, and

Fig. 10 is a fragmentary section taken on the same line as Fig. 9 but showing certain parts of the mechanism in changed positions.

Referring for the present to Figs. 1, 2 and 3, reference characters 10 and 11 designate side frames which form parts of the frame of a duplicating machine which embodies a preferred form of the invention, the frame being designated generally by the reference character 12.

Rotatably mounted in the frame 12, between the side frames 10 and 11, is a duplicating drum 13 comprising a cylindrical wall 15 and end walls 16. Mounted in the end walls 16 and extending through the duplicating drum 13 is a shaft 18 which carries a plurality of clamping members 19 adapted to clamp the leading end of a master sheet 20 against a shoulder 21 formed by a slot 22 provided in the cylindrical wall 15.

The master sheet 20 carries the data to be duplicated, the data being printed, written or typewritten thereon in reverse with ink or carbon.

Cooperating with the duplicating drum 13 is a platen or pressure roller 24 rotatably mounted by a shaft 25. When the machine is in operation, copy sheets are advanced to the bight between the duplicating drum 13 and the platen roller 24 and the platen roller 24 presses the copy sheets against the master sheet 20 so that the data on the master sheet will be duplicated on each copy sheet.

Combined feeding and moistening rollers are provided for advancing the copy sheets to the bight between the duplicating drum 13 and the platen roller 24. The combined moistening and feeding rollers are designated by the reference characters 27 and 28. The roller 27 is supplied with solvent by means comprising a perforated tube 29 which sprays the solvent upon the roller 27. A wick 30 engages the roller 27 and aids in distributing the solvent upon the roller 27. Of course the solvent is one which will dissolve the ink or carbon with which the data is formed upon the master sheet 20.

Mounted upon the frame 12 is a tray or table 32 upon which a stack of copy sheets may be placed and may be advanced manually one by one to the bight of the rollers 27 and 28. It may be mentioned that the roller 27 is driven in unison with the duplicating drum 13 when the duplicating drum is rotated. Obviously when the rollers

27 and 28 feed a sheet between them to the bight of the duplicating drum 13 and the platen roller 24, the upper side of the copy sheet will be moistened with the solvent and the moistened surface 5 will be put into contact with the data on the master sheet so that a portion of the ink or carbon thereon will be dissolved and adhere to the copy sheet.

The improved machine is driven by an electric motor (not shown). The motor drives a sheave 40 by means comprising a belt 41. The sheave 40 is mounted in the frame 12. Constrained to rotate with the sheave 40 is a smaller sheave 43 which is connected operatively to a third sheave 15 44 by a belt 45. The sheave 44 is rotatably mounted in the frame 12 and has a pinion 46 constrained to rotate with it. The pinion 46 meshes with a gear 47 with which the duplicating drum is connected operatively at the beginning 20 of each cycle of operation so that it will make a complete revolution and then come to a stop. The means for connecting the duplicating drum to the gear 47 at the beginning of each cycle of operation does not form a part of the present invention and therefore will not be described. It is sufficient to state that the duplicating drum 13, the platen roller 24 and the combined feeding and moistening rollers 27 and 28 come to a stop at the end of each cycle of operation and that a 25 copy sheet is advanced to the rollers 27 and 28 before the next cycle of operation begins.

As the copy sheets are discharged from the bight of the duplicating drum 13 and the platen roller 24, they pass into a conveyor mechanism 35 which is designated generally by the reference character 50. The conveyor mechanism 50 discharges the copy sheets into a tray 51 which is secured to the frame 12.

The conveyor mechanism is preferably in the form of a unit which is detachably secured in the frame 12. The conveyor mechanism 50 has a frame which comprises side frame members 53 and 54 which are secured to each other by means including a plurality of plates 55, 56, 57, 58 and 59 extending between the side frames 53 and 54. These plates also serve as means for guiding the copy sheets to the tray 51 as will be explained hereinafter more fully. At their lower forward ends, the side frames 53 and 54 are provided with notches 60 which are engageable by pins 61 projecting from the inner surfaces of the side frames 10 and 11. At their upper ends the side frames 53 and 54 are provided with brackets 62a having holes 62 which are engageable by pins 63 slidably and rotatably journaled in the side frames 10 and 11, the pins 63 being provided with knobs 66 at their outer ends whereby they may be manipulated. Each of the pins 63 has a smaller pin 67 extending transversely through it, the pins 67 being adapted to rest in notches 68 provided in collars 69 mounted upon the outer surfaces of the side frames 10 and 11. Springs (not shown) disposed in the side frames 10 and 11 yieldingly urge the pins 63 in directions to hold the pins 67 in the notches 68. When it is desired to release the conveyor mechanism 50 to remove it from the duplicating machine, the operator pulls outwardly upon the knobs 66 and turns the knobs through 90° and permits the pins 67 to come to rest upon the outer end surfaces of the collars 69. The pins 63 are then withdrawn from the holes 62. A pair of Z-shaped straps 70 fixed to the plate 57 are adapted to be positioned between a wall 72 and a pair of slides 73, the wall 72 being part of the frame 12 (Fig. 1). The slides 73

have lugs 75 whereby they may be manipulated by the operator. Pins 77 project through slots 78 provided in the slides 73 so that the slides are slidably mounted on the wall 72. As best illustrated in Fig. 3, the slides clamp the straps 70 to the wall 72 when they are in the positions wherein they are illustrated in Fig. 3 and it will be readily understood that they may be displaced toward each other to disengage them from the straps. Then if the pins 63 are disengaged from the holes 62 the conveyor frame may be lifted bodily from the duplicating machine.

Rotatably journaled on a stud 80 projecting from the side frame 54 is a pinion 81 which has a pinion 82 constrained to rotate with it. The pinion 82 meshes with pinions 83 and 84 fixed to shafts 85 and 86, respectively. The pinion 81 normally meshes with the pinion 46 and therefore is driven whenever the machine is in operation. Adjacent the outer surface of the side frame 53 a pulley 88 is fixed to the shaft 85 and is operatively connected to pulleys 89 and 90 by a belt 91. The pulleys 89 and 90 are fixed to shafts 93 and 94, respectively. It will be readily understood that when the pinion 81 is rotated, the shafts 86, 85, 93 and 94 will rotate in unison with the pinion 81. All the shafts will rotate in the same direction.

Mounted upon and constrained to rotate with the shaft 94 between the side frames 53 and 54 are a plurality of rollers 100 which are engageable by a plurality of knurled rollers 101 fixed to a shaft 102 which has its ends journaled in the free ends of levers 104 pivoted upon the side frames 53 and 54 by pins 105. A spring 106 which has one of its ends secured to one of the levers 104 and has the other of its ends secured to the side frame 54 yieldingly urges the levers 104 in a counter-clockwise direction (Fig. 6) to urge the rollers 101 against the rollers 100.

Fixed to the shaft 93 intermediate the side frames 53 and 54 are a plurality of rollers 110 which are engageable by knurled rollers 111 fixed to a shaft 112 which has its ends rotatably journaled in the free ends of levers 113, the levers 113 being pivoted on the side frames 53 and 54 by pins 114. Springs 115 yieldingly urge the levers in a counter-clockwise direction (Fig. 6) to hold the knurled rollers 111 in engagement with the rollers 110.

Fixed to the shaft 85 intermediate the side frames 53 and 54 are a plurality of rollers 120 which are engageable by knurled rollers 121 fixed to a shaft 122 which has its ends rotatably journaled in the free ends of levers 123, the levers 123 being pivoted by pins 124 to the side frames 53 and 54. Springs 125 yieldingly urge the levers 123 in a clockwise direction (Fig. 4) to hold the rollers 121 in engagement with the rollers 120.

Fixed to the shaft 86 intermediate the side frames 53 and 54 are a plurality of rollers 130 which are engageable by knurled rollers 131 fixed to a shaft 132 which has its ends rotatably journaled in the free ends of levers 133, the levers 133 being pivoted by pins 134 to the side frames 53 and 54. Springs 135 yieldingly urge the levers 133 in a clockwise direction (Fig. 4) to hold the rollers 131 in contact with the rollers 130.

It will be noted that the knurled rollers 101 are disposed beneath a sheet metal housing member 140 fixed to the plate 59.

The rollers 100, 110, 120 and 130 are preferably formed from resilient material such as rub-

ber, the knurled rollers 101, 111, 121, and 131 being preferably formed from metal.

When the improved machine is in operation, the drum 13 rotates in a counter-clockwise direction (Fig. 1) and the platen roller 24 rotates in a clockwise direction (Fig. 1). The driven rollers 130, 120, 110 and 100 are driven in a clockwise direction (Fig. 1) and they, of course, drive the knurled rollers.

Obviously, when the copy sheets pass from between the drum 13 and the platen roller 24, they are guided by the plate 55 to the rollers 130 and 131 which advance them over the plate 56 to the rollers 120 and 121. The rollers 120 and 121 then advance them to the rollers 110 and 111 and the copy sheets are advanced by these rollers to the rollers 100 and 101 which discharge the copy sheets upon the tray 51. The plate 57 guides the copy sheets from the rollers 120 and 121 to the rollers 110 and 111 and the plates 58 and 59 guide the copy sheets from the rollers 110 and 111 to the rollers 100 and 101.

It will be readily understood that although the copy sheets pass beneath the drum 13 during the duplicating operation, the conveyor mechanism 50 brings the copy sheets to a point near the top of the drum before they are discharged upon the tray 51. The tray 51 is in such a position that the operator may view the copy sheets as they are deposited thereon. Also, the operator may view the sheets as they are being discharged from the rollers 100 and 101. If the operator notes that the copy sheets are not satisfactory, the machine may be stopped and adjusted as desired.

Referring now to Figs. 7 to 10, inclusive, wherein conveyor mechanism 50a is shown, which conveyor mechanism embodies another form of the invention, it will be noted that parts of the conveyor mechanism 50a are identical in construction with parts of the conveyor mechanism

50. The only difference between the two structures is at the upper ends of these mechanisms. The parts of the conveyor mechanism 50a that are substantially identical with parts of the conveyor mechanism 50 are identified by the same numerals with the letter *a* added thereto. It will be noted that the uppermost knurled rollers 101a which correspond to the rollers 101 are fixed to a shaft 102a that has its ends rotatably journaled in brackets 150 fixed to the inner side of a housing-like member 151 provided with downwardly extending flanges 152 at its ends. Pins 153 pivot the flanges 152 to the upper ends of bars 155 which are secured to the side frames 54a and 53a by screws 156. A guide plate 157 is fixed to the under surface of the housing member 151 and is adapted to guide the copy sheets to the bight of the knurled rollers 101a and the cooperating rollers 100a when the apparatus is in the position wherein it is shown in Fig. 9. However, if it is so desired, the housing member 151 may be swung from the position wherein it is shown in Fig. 9 to the position wherein it is shown in Fig. 10 so that the guide plate 157 and the knurled rollers 101a occupy the positions wherein they are shown in Fig. 10 so that access may be had to the rollers 101a to clean them. Also, if it is so desired, the apparatus may be adjusted as shown in Fig. 10 to permit the copy sheets to pass directly upward from the conveyor into the hands of the operator.

While the preferred embodiment of the invention has been shown and described, it is to be understood that it is capable of many modi-

fications. Changes, therefore, in the construction and arrangement may be made without departing from the spirit and scope of the invention as disclosed in the appended claims in which it is the intention to claim all novelty inherent in the invention as broadly as possible in view of the prior art.

Having thus described the invention, what we claim as new and desire to secure by Letters Patent is:

1. In a paper handling mechanism for a duplicating machine having a drum at the lower portion of which printed copy sheets are released, the combination of a plurality of pairs of rollers to which said copy sheets are delivered successively for moving the sheets upwardly about the delivery side of the drum, guide plates between successive pairs of rollers for deflecting the sheets inwardly toward the drum slightly from each pair of rollers and into the bite of the next pair, a tray positioned opposite to the upper portion of the drum into which said sheets are fed by the last pair of rollers, and means for driving said rollers.

2. In a paper handling mechanism for a duplicating machine having a drum at the lower portion of which printed copy sheets are released, the combination of a frame comprising edgewise bowed frame plates connected together by a series of spaced guide plates so as to be held rigidly in position with respect to each other, a series of pairs of rollers to which said copy sheets are delivered successively for moving the sheets upwardly about the delivery side of the drum, said guide plates being interposed between successive pairs of rollers so as to direct the sheets from one pair to the next about the face of the drum, a tray positioned opposite to the upper portion of the drum into which said sheets are fed by the last pair of rollers into position to be visible to the operator as they are piled in the tray, and means for driving said rollers.

3. In a paper handling mechanism for a duplicating machine having a drum at the lower portion of which printed copy sheets are released, the combination of a frame comprising edgewise bowed frame plates connected together by a series of spaced guide plates so as to be held rigidly in position with respect to each other, a series of pairs of rollers to which said copy sheets are delivered successively for moving the sheets upwardly about the delivery side of the drum, said guide plates being interposed between successive pairs of rollers so as to direct the sheets from one pair to the next about the face of the drum, a tray positioned opposite to the upper portion of the drum into which said sheets are fed by the last pair of rollers into position to be visible to the operator as they are piled in the tray, tongue and groove connecting means for holding the lower end portion of said frame releasably in position on the machine, brackets extending from an intermediate portion of said frame, means for securing said brackets releasably in position on the machine for holding the frame removably in position, and means for driving said rollers.

4. In a paper handling mechanism for a duplicating machine having a drum at the lower portion of which printed copy sheets are released, the combination of a frame comprising edgewise bowed frame plates connected together by a series of spaced guide plates so as to be held rigidly in position with respect to each other, a series of pairs of rollers to which said copy sheets are delivered successively for moving the sheets upwardly about the delivery side of the drum, said guide

plates being interposed between successive pairs of rollers so as to direct the sheets from one pair to the next about the face of the drum, a tray positioned opposite to the upper portion of the drum 5 into which said sheets are fed by the last pair of rollers into position to be visible to the operator as they are piled in the tray, tongue and groove connecting means for holding the lower end portion of said frame releasably in position on the machine, brackets extending from an intermediate 10 portion of said frame, slide bars on the machine adapted in operative position to engage said brackets for holding them releasably in position so as to maintain the frame removably in operative 15 position, and means for driving said rollers.

5. In a paper handling mechanism for a duplicating machine having a drum at the lower portion of which printed copy sheets are released, the combination of a plurality of pairs of rollers to 20 which said copy sheets are delivered successively for moving the sheets upwardly about the delivery side of the drum, guide plates between successive pairs of rollers for directing the sheets from each 25 pair of rollers into the bite of the next pair, a tray positioned opposite to the upper portion of the drum, movably mounted guide means in connection with the uppermost pair of rollers adapted in operative position to direct the copy sheets into 30 said tray and adapted in changed position to permit the sheets to move upwardly into position to be grasped by the operator, and means for driving 35 said rollers.

6. In a paper handling mechanism for a duplicating machine having a drum at the lower portion of which printed copy sheets are released, the combination of a plurality of pairs of rollers to which said copy sheets are delivered successively for moving the sheets upwardly about the deliv-

ery side of the drum, guide plates between successive pairs of rollers for directing the sheets from each pair of rollers into the bite of the next pair, one of the rollers of the last pair of rollers being 5 movably mounted so as to be capable of being moved out of operative position with respect to the other roller of the same pair, a tray positioned opposite to said last pair of rollers, a guide plate mounted so as to move with said movable roller adapted when the plate and roller are in normal position to direct copy sheets into said tray and adapted when moved out of operative position to permit the sheets to move upwardly into position to be grasped by the operator, and means for rotating said rollers.

7. In a paper handling mechanism for a duplicating machine having a drum at the lower portion of which printed copy sheets are released, the combination of a plurality of pairs of rollers to which said copy sheets are delivered successively for moving the sheets upwardly about the delivery side of the drum, guide plates between successive pairs of rollers for directing the sheets from each pair of rollers into the bite of the next pair, a guide plate pivotally mounted so as to swing about one edge of the plate adjacent to the topmost pair of rollers, the upper roller of said uppermost pair being rotatably mounted upon said guide plate, a tray positioned opposite to said uppermost pair of rollers, the arrangement being such that when the guide plate and roller are in operative position copy sheets are directed by said guide plate into the tray and that when the guide plate and roller are moved out of operative position the copy sheets are moved upwardly into position to be 30 grasped by the operator, and means for rotating 35 said rollers.

ALFRED MARCHEV.
ROBERT F. MORRISON.
